UNITED STATES PATENT OFFICE.

WILLIAM A. BENTON, OF FORT WORTH, TEXAS.

MOLD FOR MAKING CONCRETE BLOCKS AND ARTIFICIAL STONE.

No. 856,213.

Specification of Letters Patent.

Patented June 11, 1907.

Application filed April 30, 1906. Serial No. 314,497.

To all whom it may concern:

Be it known that I, WILLIAM A. BENTON, a citizen of the United States, residing at Fort Worth, Texas, have invented certain new and useful Improvements in Molds for Making Concrete Blocks or Artificial Stone, of which the following is a specification.

This invention relates to devices for manufacturing concrete blocks and the object is to provide simple and inexpensive molds, which are light and easily transported or handled, for molding and moving concrete blocks.

One of the advantages of this invention is that no pallet is needed for receiving the block when formed because the blocks may be turned out on sand.

Other objects and advantages will be fully explained in the following description and the invention will be more particularly pointed out in the claims.

Reference is had to the accompanying drawings which form a part of this application and specification.

Figure 1 is a plan view of a mold coupled together as when in service. Fig. 2 is a longitudinal section taken along the line *x* *x* of Fig. 1. Fig. 3 is a plan view of the removable core. Fig. 4 is a plan view of a facing for forming the outside faces of concrete blocks, this form of facing being replaceable with the facing shown in Fig. 2. Fig. 5 is an end view of a concrete block turned on the edge. Fig. 6 is a plan view of the same.

Similar characters of reference are used to indicate the same parts throughout the several views.

A frame is provided which consists of side pieces 1 and 2, end piece 3 hinged to the side pieces 1 and 2 and end piece 4 hinged to the side piece 2. The end piece 4 is connected to the side piece 1 by suitable latches 5. The frame thus described carries side molding pieces 6 and 7 and end molding pieces 8 and 9. The hinges are indicated by 10. The side molding pieces 6 and 7 and the end molding pieces 8 and 9 may carry any suitable blocks for forming creases or cut-outs in the concrete blocks.

In the drawings I show half cylindrical blocks 11 which would form the curved creases 12 shown in Figs. 5 and 6. The end pieces 8 and 9 carry the irregular forms 13 which form the creases or cut-outs 14 shown in Figs. 5 and 6. In making the blocks for a door or window facing one of the blocks 13 must be removed so that a smooth surface

will be formed instead of the cut-out 14 in that end of the block next to the window or door. The outside face, or face exposed to the weather, of the concrete blocks is formed 60 downward in the mold as indicated in Fig. 2.

The surface 15 of the block shown in Figs. 5 and 6 is formed by the irregularly shaped piece of copper 16 shown in Fig. 2. Molding 17 is used to form a bed for cement which is 65 used between the blocks to hold the blocks together. The piece of copper 16 is secured or fastened to a box 18 as shown in Fig. 2. The copper facing 16 may be formed into any suitable ornamental design. 70

In Fig. 4 I show a panel facing which is replaceable with facing 16 shown in Fig. 2. In forming the end of a block which is to be placed in the corner of a house, a facing similar to the facing 16 or the facing 19 shown in Fig. 4 would have to be used instead of one of the facings or molding pieces 8 or 9, so that the corners of the house would have the same design as the other parts of the house. 75

A removable core 20 is provided for making 80 the blocks lighter and also for providing that openings may be made vertically through the molds. The inner end 21 of the core may be made slightly smaller than the opposite end so that the core will be tapering 85 and easily withdrawn from the concrete block. A draw-bar 22 is attached to the core 20 for drawing the core out of the block. Hand screws 23 are screw-threaded into the draw-bar 22 for forcing the core out of the 90 concrete block. When the screws 23 are

turned the inner ends of the screws or bolts 23 press against the outside frame piece 1 to force the core out of the concrete block before the concrete block is removed from the 95 molds.

The core 20 is inserted through the sides of the frame 1 and through the molding piece 6 and the core is withdrawn in the manner stated, so that there will be no injury whatever to the concrete block. The 100 screws press against the side piece 1 to withdraw the core and the concrete block will press against the inner face of the molding piece 6 while the core is being withdrawn.

Thus the concrete block will remain perfectly stationary while the core is being removed. 105

In practice the mold is coupled together as shown in Fig. 1 with the core removed. The material is placed in the mold and tamped, 110 that part of the mold adjacent to facing 16 being provided with a greater proportion of

cement for the purpose of making the outside facing of the blocks stronger and harder than the other part of the blocks. The material is tamped in the mold up even with the bottom of the core 20, so that the material will be flush with the core when the core is inserted. The core is then inserted and the mold completely filled until it is level with the top of the side and end pieces 6, 7, 8 and 9. The core 20 can then be removed by drawing out the core with the screw bolts 23 and the mold uncoupled so that the side and end pieces may be removed. The concrete block can then be tilted over on the side in sand. The mold can then be coupled together for receiving another concrete block. If necessary the mold with the concrete block can be transported to any suitable place and for this reason handles 24 are attached to the end pieces.

Having fully described my invention, what I claim as new and desire to secure by Letters Patent, is,—

1. A mold having side and end frame pieces connected together and capable of outward movement, molding pieces carried by said frame pieces, configuring blocks carried by said molding pieces, a core inserted horizontally through one of said sides and through the molding piece on that side and intercepting the configuring blocks on both sides, a draw bar attached to said core and

resting against the outside frame piece, hand-screws in the plane of said core operating through said draw-bar and bearing against the outside frame piece in close proximity to the opening in said frame piece for said core and causing a gradual outward thrust of said core, and a facing mold of suitable design for forming the weather face of blocks. 35

2. A mold having a weather face molding piece of suitable design forming the bottom of the mold, side and end frame pieces hinged together at three corners, suitable latches for connecting the frame pieces together at the fourth corner, side and end molding pieces carried by said frame pieces, a core inserted horizontally through one side of said mold and abutting against the inside of the other side of said mold, a draw-bar attached to said core and resting against the outside of the frame piece on that side, and hand screws operating through said draw-bar in the plane of said core and bearing against the outside frame piece in close proximity to said core 50 for causing a gradual thrust of said core in removing the same from said mold.

In testimony whereof, I set my hand in the presence of two witnesses, this 16th day of April, 1906.

WILLIAM A. BENTON.
